(57) **CLAIM**

The ornamental design for a display and operating panel, as shown and described.

DESCRIPTION

FIG. 1 is a front perspective view of a display and operating panel showing my new design according to a first embodiment;

FIG. 2 is a side perspective view thereof;

FIG. 3 is a rear elevation view thereof;

FIG. 4 is a front elevation view thereof;

FIG. 5 is a bottom plan view thereof;

FIG. 6 is a top plan view thereof;

FIG. 7 is a right side elevation view thereof; and

FIG. 8 is a left side elevation view thereof.

FIG. 9 is a front perspective view of a display and operating panel showing my new design according to a second embodiment;

FIG. 10 is a side perspective view thereof;

FIG. 11 is a rear elevation view thereof;

FIG. 12 is a front elevation view thereof;

FIG. 13 is a bottom plan view thereof;

FIG. 14 is a top plan view thereof;

FIG. 15 is a right side elevation view thereof; and,

FIG. 16 is a left side elevation view thereof.

The broken lines illustrate portions of the display and operating panel that form no part of the claimed design.

1 Claim, 6 Drawing Sheets
